AIR-DRAG APPARATUS FOR MISSILES
George Chakopian, Lincoln, and Russell T. Crowell, East Greenwich, R.I., and Alfred Ouellette, Brockton, Mass., assignors to the United States of America as represented by the Secretary of the Navy

Filed July 18, 1963, Ser. No. 296,143
12 Claims. (Cl. 244—113)

This invention relates to an apparatus for use in an air-to-sea missile delivery system. More particularly, this invention relates to an apparatus for use in the control of the trajectory of an airborne missile.

In the past, airborne torpedoes were conventionally delivered to their respective water-borne targets by aircraft which today may be considered to be of the low speed variety. With the advent of high speed jet aircraft, however, a need has come into existence for a delivery system possessing a greater degree of accuracy than heretofore required.

One of the major factors affecting the accuracy of delivery of air-to-sea missiles is trajectory control. In order to have a consistently reproducible trajectory, and greater accuracy, it is necessary to control the missile from time of launch to immediately prior to water entry. This would include control of deceleration in conjunction with positive stabilization of the missile throughout all phases of its descending flight.

Due to the launching speeds involved and the relatively small target area, trajectory control is essential. The major causes of trajectory inaccuracies are variations in operating time between time of launch and the operation of the stabilization equipment during descent. The missile must be decelerated from a launch velocity of about 500 knots to a terminal velocity of about 80 knots along a controlled trajectory without a lapse of time between operations where free fall would be experienced. Also, torpedo oscillations must be compensated for during this deceleration in order to prevent damage to the torpedo.

The subject invention fulfills the needs described by providing deceleration, stabilization, and control trajectory to torpedoes launched from aircraft at speeds of the order of 500 knots. It also provides accuracy of delivery to a specified target by providing a constant drag force on the missile throughout its initial delivery trajectory.

An object of this invention is to provide an apparatus for use in an air-to-sea delivery system.

Another object is to provide an apparatus for the control of the trajectory of an airborne missile.

A further object is to provide an apparatus for the retardation and stabilization of an airborne missile during its descending flight.

Other objects and many of the attendant advantages of this invention will be readily appreciated as the same become better understood by reference to the following detailed description when considered in connection with the accompanying drawing wherein:

FIG. 1 is a perspective view of the apparatus showing the details of construction;

FIG. 2 is a side view showing the apparatus operatively carried by an aircraft;

FIG. 3 is a side view of the apparatus in the initial stage of opening;

FIG. 4 is a perspective view of the apparatus in the intermediate stage of opening;

FIG. 5 is a side view, partly in section, taken on line 5—5 of FIG. 3 showing in detail the flow control unit of the apparatus;

FIGS. 6 to 9 are side views partly in section, of the flow control unit, showing the sequence of operation during the performance of the apparatus; and

2

FIG. 10 is a perspective view showing the separation of the apparatus from the missile prior to water entry; FIG. 11 is a schematic view showing the apparatus of this invention.

5 Similar numerals refer to similar parts throughout the several views.

As shown in FIG. 1, the device is composed of a plurality of vanes 11 and 12, some of which 11 are partially free moving and some of which 12 have their movements totally controlled by a central hydraulic system 13. All of the vanes are pivotally mounted exteriorly upon the end portion of a hydraulic cylinder 14 and each of the vanes is interconnected to the adjacent vanes by a series of fabric strips 15. The cylinder 14 is provided with a piston 15' slidably mounted on a central shaft 16 which is axially secured to the interior of the closed end of the cylinder 14. The piston 15' is provided with a collar 16' operatively connected to every other vane 12 by means of a link-rod assembly 17 which controls all the pivotal movements of such vanes 12. The cylinder 14 which contains a disposable oil 18, is also provided with a flexible hose 19 affixed to the cylinder and communicating between the oil reservoir and the flow regulating unit 21 to be hereinafter described.

25 Referring to FIG. 2, the device is secured to the rear portion of the torpedo 22 by an air frame 23 which fits around the body of the missile. Prior to use, all the vanes are in the retracted position, the controlled vanes 12 forming an inner core around the hydraulic system 13 and the partially free moving vanes 11, which are closely aligned when retracted, forming an outer shell 24 for the unit. A locking band 25, which holds the partially free moving vanes 11 in position, is provided with an electrically actuated pyrotechnic reefing line-cutter 26 having the ability to instantaneously sever a 3000 pound nylon line with no escaping flame or heat to cause damage to surrounding materials. Once severed, a band retraction mechanism 27 composed of four spring and cable assemblies, will pull the band in the forward direction and hold it in position against the high velocity air stream. This action removes the clamping band from the outer vanes and prevents the possibility of the loose band striking the aircraft.

With the bands removed, springs 28 located in the rest pads 29 under the end portion of the vanes forming the outer shell will cause such vanes 11 to pivot open a sufficient amount to permit the high velocity air stream to enter, forcing such vanes to suddenly open to an angle of about 31° as shown in FIG. 3. This condition is estimated to produce a drag having a load value of approximately 2250 pounds at a launch velocity of 500 knots at 500 feet. The outer vanes 11, which were free moving up this point, are now restrained from further movement by the fabric snubbing strips 15 which join such vanes to the inner control vanes 12. The load of opening shock is transmitted from the outer moving vanes 11 through the fabric strips 15 to the inner control vanes 12 whose movements are controlled by a hydraulic system hereinafter described. The vanes 11, 12 and the fabric strips 15 form the structure which provides the drag producing surfaces. Any additional increase in drag area of the device is of a controlled nature from this point on. The device, which is functioning as an air-brake, will continue to open at a rate which will provide a constant drag of about 3000 pounds.

As shown in FIG. 4, the control vanes 12 are operatively connected to a hydraulic system 13 which serves to resist the opening movements of the vanes 12 against the force provided by dynamic air pressure. As heretofore described, the hydraulic system 13 is composed of a cylinder 14 provided with a piston 15' having a collar 16' operatively connected to each of the control

vanes 12 by a separate link-rod assembly 17. The cylinder 13 contains oil 18 and is provided with a hose 19 connecting the reservoir of oil 18 within the cylinder 14 to a flow control unit 21. As the control vanes 12 begin to open from the position shown in FIG. 3 to that shown in FIG. 4, the piston 15', which is guided on the center shaft 16 is caused to move into the cylinder 14. As a result, the pressure on the oil 18 increases forcing the oil out of the cylinder 13 into the hose 19 which directs it to a flow control unit 21 for programmed metering. It is this programmed metering of oil which maintains a constant drag during the opening of the device. When the device is fully open, as shown in FIG. 1, the drag will begin to diminish below the 3000 pound level.

Programmed metering of the oil from the cylinder 14 through the hose 19 is accomplished by a flow control unit 21 which is shown in FIG. 5. This unit, by controlling the rate of flow of oil 18 from the cylinder 14, regulates the outward movement of the control vanes 12 and the effective area of the air brake, thereby maintaining a constant drag on the descent of the missile. However, this unit, in turn, is regulated by the pressure developed by a closed circuit hydraulic system 31, in response to movements of the central shaft 16.

The closed circuit hydraulic system 31 is composed of a reservoir 32 provided with a pressure shoe 33 responsive to movements of the central shaft 16. The reservoir 32 is circumferentially disposed around the lower portion of the shaft 16 which passes through the mounting 34 secured to the airframe 23. As shown, the reservoir is defined by the shaft 16, the interior surface of the mounting 35, the flow control unit 36, and the pressure shoe 33. The latter shoe 33 because it is secured to the central shaft 16 regulates the operational area of the reservoir 32 in response to movements of the shaft 16.

The flow control unit 21 is provided with a housing 38 having a high pressure chamber 39 within which is mounted a spring loaded hollow piston 41 of closed end construction. The head 42 of the hollow piston communicates with the reservoir 32, heretofore described, and the movement of the piston 41 in the chamber 39 is responsive to changes in pressure in the reservoir 32 caused by the constrictive movement of the pressure shoe 33 on the central shaft 16. The lower portion of the hollow piston 41 is in contact with a plate 42 backed by a plurality of balancing springs 43 which, to some extent, function to maintain a constant inward pressure on the piston 41 enabling it to remain at all times in contact with the fluid in the reservoir 32.

The housing 38 of the unit is provided with an inlet chamber 44 and an exhaust chamber 45, both of which communicate with the pressure chamber 39 wherein the hollow piston 41 is mounted. The inlet chamber 44 is provided with an inlet fitting 46, which communicates with the exhaust hose 19, while the exhaust chamber 45 is provided with an exhaust fitting 47 which communicates with the atmosphere. The body of the hollow piston 41 is provided with a plurality of holes in spaced relationship around the periphery thereof, which in combination with the inlet chamber 44 and the exhaust chamber 45 form two variable orifices.

When one course 48 of holes on the upper portion of the piston 41 align themselves with the inlet chamber 44, another course of holes 49 on the lower portion of the piston 41 will align themselves with the exhaust chamber 45 and the hollow body will function as a by-pass port for the travel of oil from the inlet fitting 46 to the exhaust fitting 47. In the non-operative condition, prior to use, the edges of the holes are directly in line with the edges of the chamber separation sleeve 51 and in this position, the metering orifice is fully open, as shown. This alignment depends on the position of the piston 41 in the chamber 39, which is direct-

ly influenced by the pressure exerted by the reservoir 32 and is hereinafter described in detail. It is the force relationship between the balancing spring 43 and the fluid pressure in the reservoir 32 that positions the piston 41 to the required orifice area.

Upon initial shock, when the vanes 11 open to their initial position, as shown in FIG. 2, the vane 11 develops a drag and the load of such drag pulls the shaft 16 outwardly through the mounting 34. As a result, the pressure shoe 33 attached to the central shaft 16 constricts the area of the reservoir 32 developing a pressure which, in turn, is transmitted to the head 42 of the piston 41. This is because the piston 41 forms a part of the closed circuit hydraulic system 31 as shown in FIG. 5. This action forces the body of the piston 41 outwardly against the spring actuated plate 42, and the upper course 48 of holes adjacent the inlet chamber 44 are moved into alignment with the separation sleeve 51 between the inlet chamber 44 and the exhaust chamber 45. In this position, the inlet port is fully closed, as shown in FIG. 6.

At this point, the flow of oil from the main cylinder into the hose 19 is restricted and a back-pressure builds up in the main cylinder 14 preventing further movement of the piston 15' and the related movement of the vanes 12. When the vanes 12 are locked in position, as described, the area of drag defined by the vanes 11, 12 and the snubbing strips 15 assumes a set value. As a result, the descending torpedo is decelerated but the drag developed by the defined area of the device decreases and a lesser load is transmitted through the central shaft 16 to the pressure shoe 33. As the latter shoe releases its pressure on the confined reservoir 32, the springs 43, in sequence, overcome the pressure transmitted to the piston head 42 by the reservoir 32. The piston will then oscillate in an inward direction against the reservoir 32 through the position shown in FIG. 7 to the position shown in FIG. 8.

As shown in FIG. 8, the inlet port is open and the oil 18 exhausting from the main cylinder 14 enters the valve metering chamber through the inlet fitting 19. When the oil is restricted in the chamber, the pressure therein will equal the pressure in the main cylinder minus negligible pressure losses due to the length of connecting line from the cylinder to the flow control unit. The oil will then meter through the variable orifice into the by-pass port of the piston body and through the plurality of exhaust holes 49 into the exhaust chamber 45 and out to the atmosphere through the exhaust fitting 47. There is a substantial difference between the area of the metering orifice 48 and the exhaust fitting 47, and as a result the oil will be exhausted to the atmosphere at a considerably lower pressure than the pressure in the system. The maximum exhaust pressure has been estimated to be about 37 p.s.i.

When the main cylinder 14 is relieved of some amount of oil 18, the main piston 15' therein will move further into the cylinder 14 and the vanes 12, in turn, will be allowed to pivot further in an outwardly direction. This develops a greater drag due to the increased area and an increased load is transmitted to the central shaft 16 promoting the sequence of operations heretofore encountered upon initial shock. These operations will continue until the flow control unit 21 assumes the position shown in FIG. 9 when the oil is fully exhausted from the main cylinder and the device progresses to the fully open position as shown in FIG. 1. Prior to this, whenever the drag-load decreases, the valve through the described sequence of operations will open and whenever the drag-load increases, the valve again will be closed as heretofore explained.

As described, the drag load is sensed by the linear movement of the center shaft along the longitudinal axis of the air-brake. The drag loads acting on the air-brake vanes are transmitted to the close circuit hydraulic system of the flow control unit by two paths. One path is from the vanes through the link-rods to the main piston which

fits in the cylinder attached to the center shaft. The other path is directly from the vanes through the pivot pins to the center shaft. The amount of force transmitted through each path varies as the air-brake opens to its full diameter. This is because of the continually increasing angle of the link-rods which connect the main vanes with the piston. However, the closed circuit hydraulic system of the flow control unit always receives the total drag load because the loads from the two sources are transmitted through one common shaft. The drag force is thus sensed by generating a fluid pressure in the reservoir and this pressure serves to set the metering area of the flow control unit.

At a predetermined altitude, the air frame and the air-braking device will be jettisoned. This may be accomplished by means of a timing device which will initiate the release mechanism prior to water impact so that all suspension and stabilization equipment will be cleared of the torpedo. Air delivery of the torpedo will have been completed as shown in FIG. 10, and the torpedo will be ready for its water trajectory without any risk of propeller damage or bent shaft.

Obviously, many modifications and variations of the present invention are possible in the light of the above teaching. For instance, when the air-brake is inoperative, prior to use, the oil from the main cylinder may be prevented from leaking by means of a plug which may be fitted over the exhaust fitting. Immediately upon the initial opening of the device, the oil pressure in the system builds up and the plug will be jettisoned. It is therefore to be understood that within the scope of the appended claims, the invention may be practiced otherwise than as specifically described.

We claim:

1. An apparatus for use in the retardation and stabilization of airborne missiles during descending flight comprising

hydraulic means having a base member,
a plurality of vane members pivotally mounted in spaced relationship around said base member,
each of said vane members being interconnected to adjacent vane members by a plurality of webbing members,
every other of said vane members having a body portion coupled through mechanical linkage to said hydraulic means whereby a compressive pressure is transmitted from said vane members through said mechanical linkage to said hydraulic means when dynamic air pressure acts on said vane members,

said compressive pressure forcing fluid from said hydraulic means, and

valving means cooperating with said hydraulic means for the programmed metering of said fluid from said hydraulic means, thereby controlling the pivotal movement of said vane members on said base.

2. An apparatus for use in the retardation and stabilization of airborne missiles during descending flight comprising

hydraulic means having a base member,
a plurality of vane members pivotally mounted in spaced relationship around said base member,
each of said vane members interconnected to adjacent vane members by a plurality of webbing members,
every other of said vane members having a body portion coupled through mechanical linkage to said hydraulic means whereby a compressive pressure is transmitted from said vane members through said mechanical linkage to said hydraulic means when dynamic air pressure acts on said vane members,

said compressive pressure forcing fluid from said hydraulic means, and

valving means connected to said hydraulic means for

the programmed metering of said fluid from said hydraulic means in response to movements of said base by variations of total load of drag transmitted from said vane members and said webbing members to said base thereby controlling the pivotal movement of said vane members on said base.

3. An apparatus for use in the retardation and stabilization of airborne missiles during descending flight comprising

hydraulic means having a base member,
a plurality of vane members pivotally mounted in spaced relationship around said base member,
a plurality of webbing members interconnecting each of said vanes to adjacent vane members,
a mechanical linkage connecting the body portion of every other of said vanes to said hydraulic means whereby compressive pressure is transmitted from said vane members through said linkage to said hydraulic means when dynamic air pressure acts on said vane members,

said compressive pressure forcing fluid from said hydraulic means, and

valving means connected to said hydraulic means for the programmed metering of said fluid from said hydraulic means thereby controlling the pivotal movement of said vane members on said base.

4. An apparatus for use in the retardation and stabilization of airborne missiles during descending flight comprising

hydraulic means having a base member,
a plurality of vane members pivotally mounted in spaced relationship around said base member,
a plurality of webbing members interconnecting each of said vanes to adjacent vane members,
a mechanical linkage connecting the body portion of every other of said vanes to said hydraulic means whereby compressive pressure is transmitted from said vane members through said linkage to said hydraulic means when dynamic air pressure acts on said vane members,

said compressive pressure forcing fluid from said hydraulic means, and

valving means connected to said hydraulic means for the programmed metering of said fluid from said hydraulic means in response to movements of said base by variations of total load of drag transmitted from said vane members and said webbing members to said base thereby controlling the pivotal movement of said vane members on said base.

5. An apparatus for use in the retardation and stabilization of airborne missiles during descending flight comprising

a hydraulic cylinder within which is housed a fluid,
said cylinder fitted with a movable piston having a dependent rod provided with a collar,
a shaft passing axially through said collar, rod, and piston and having one end axially secured within said cylinder,
a flow line integral said cylinder and communicating with said fluid,
a pressure-regulated valve fitted on said line and controlling the flow of said fluid in said line,

said valve communicating with a reservoir within which is housed a pressure means,

said pressure means integral the free end of said shaft and responsive in changes of pressure to movements of said shaft, and a plurality of vanes pivotally mounted on the exterior of said cylinder,

each of said vanes being interconnected to another by means of webbing and every other of said vanes having a mid-portion connected to said collar by means of a tie-bar.

6. An apparatus for use in the retardation and stabiliza-

tion of airborne missiles during descending flight comprising:

- a hydraulic cylinder fitted with a movable piston having a dependent rod around which is a collar,
- said cylinder containing a disposable fluid,
- a plurality of vanes pivotally mounted in spaced relation exteriorly on the end portion of said cylinder,
- each of said vanes being interconnected to adjacent vanes by webbing,
- a plurality of tie-rods connecting the mid-portion of 10 said vanes to said collar,
- a longitudinally movable shaft passing axially through said collar, said rod, and said piston and axially secured within said cylinder,
- said shaft provided with a pressure shoe,
- a pressure actuated valve provided with a pressure transmitting reservoir communicating with said valve, 20 said reservoir containing a second fluid and housing said pressure shoe,
- a flow-line communicating between said disposable fluid in said cylinder and said valve.

7. An apparatus for use in the retardation and stabilization of airborne missiles during descending flight comprising:

- a hydraulic cylinder fitted with a movable piston having 25 a dependent rod around which is a collar,
- said cylinder containing a disposable fluid,
- a plurality of vanes pivotally mounted exteriorly on said cylinder,
- each of said vanes being interconnected to adjacent 30 vanes by webbing,
- a plurality of tie-rods connecting every other of said vanes to said collar,
- a longitudinally movable shaft passing through said collar, said rod, and said piston and secured within 35 said cylinder,
- said shaft provided with a pressure shoe,
- a pressure actuated valve provided with a pressure transmitting reservoir communicating with said valve, 40 said reservoir containing a second fluid and housing said pressure shoe whereby pressure is transmitted from said shaft by means of said shoe through said reservoir to open and close said valve, and
- a flow-line communicating between said disposable fluid in said cylinder and said valve whereby said fluid flows through said flow line to said valve responsive to movements of said piston by said vanes through said tie-rods.

8. An apparatus for use in the retardation and stabilization of airborne missile comprising:

- a cylinder one end of which is open,
- said cylinder containing a disposable oil,
- an elongated central shaft one end of which is axially 55 secured within said cylinder and the other end of which axially extends out of said cylinder,
- a piston having a dependent rod provided with a collar,
- said piston, rod, and collar slidably mounted on 60 said shaft and said piston operatively fitted in said cylinder,
- a flow-line communicating with said disposable oil through the side of said cylinder,
- a spring-actuated valve provided on said flow-line for control of the flow of said oil in said line,
- a pressure shoe provided on said shaft, 65
- a reservoir containing a control fluid communicating with said adjustable valve,
- said reservoir housing said pressure shoe for the compression of said control fluid,
- said control fluid transmitting pressure to said 70 adjustable valve thereby controlling the flow of said disposable fluid from said cylinder, and
- a plurality of vanes pivotally mounted in spaced relationship exteriorly around said cylinder,

each of said vanes interconnected to the adjacent vanes by a plurality of webbing members, every other of said vane members mechanically linked to said collar.

9. An apparatus for use in the retardation and stabilization of airborne missiles comprising:

- a cylinder one end of which is of closed construction and the other end of which is open,
- said cylinder containing a disposable fluid,
- an elongated central shaft one end of which is secured to said closed end of said cylinder and the other end of which extends axially out of said cylinder,
- a piston having a dependent rod provided with a collar, 10 said piston, rod, and collar slidably mounted on said shaft and said piston operatively fitted in said cylinder,
- a flow-line communicating with said disposable fluid through the side of said cylinder,
- a spring-actuated valve provided on said flow-line for control of the flow of said fluid in said line,
- a pressure shoe provided on said shaft,
- a reservoir containing a control fluid communicating 15 with said adjustable valve,
- said reservoir housing said pressure shoe for the compression of said control fluid,
- said control fluid transmitting pressure to said adjustable valve thereby controlling the flow of said disposable fluid from said cylinder,
- a plurality of free moving vanes one end of each of which is pivotally mounted exteriorly on said closed end of said cylinder,
- a plurality of control vanes one end of each of which is pivotally mounted exteriorly on said closed end of said cylinder and
- a plurality of tie-rods operatively connecting the mid-portion of said control vanes to said collar, and
- a plurality of webbing members interconnecting said free moving vanes with said control vanes.

10. An apparatus for use in the retardation and stabilization of airborne missiles comprising:

- a cylinder having one end of open construction and the other of closed construction,
- said cylinder containing a disposable oil, an elongated shaft having one end axially secured to the closed end of said cylinder,
- a piston being operatively fitted in the open end of said cylinder and slidably mounted on said shaft,
- said piston having a dependent rod provided with a collar,
- a flow-line integral said cylinder and communicating with said oil,
- a spring-actuated valve on said flow-line for control of said oil,
- a reservoir having a passage communicating with said valve,
- said reservoir containing a second fluid,
- a pressure shoe provided on the free end of said shaft and housed in said reservoir,
- said shoe transmitting pressure to said valve through said second fluid thereby controlling flow in said line,
- a plurality of control vanes having one end pivotally mounted on the outer surface of said cylinder,
- a plurality of tie-rods operatively connecting the mid-portion of said control vanes to said collar,
- a plurality of free moving vanes having one end pivotally mounted on the outer surface of said cylinder, and
- a plurality of webbing members operatively connecting said free moving vanes to said adjacent control vanes whereby,
- said piston, responsive to movement of said vanes, forces oil from said cylinder into said line and said valve controls the dispensing of oil from said line responsive to movements of said shaft.

11. A valve for use in an air-to-sea missile delivery system comprising:

a body member having an elongated chamber of open end construction provided with an inlet fitting and an exhaust fitting,

a longitudinally movable hollow cylinder of closed end construction housed in said chambers,

said cylinder provided with a peripheral array of orifices around the upper and lower portion thereof,

10 said upper array of orifices aligned with said inlet fitting and said lower array of orifices aligned with said exhaust fitting whereby fluid may flow from said inlet fitting through said upper orifice array into said cylinder 15 and out said lower orifice array into said exhaust fitting,

a closed circuit hydraulic system communicating with the upper end of said cylinder,

said system transmitting a varying downward pressure to said cylinder, and

20 a spring-actuated plate in contact with the lower end of said cylinder,

said plate transmitting an upper pressure to said cylinder

25 whereby in response to an overbearing downward pressure, said cylinder moves along the longitudinal axis of said chamber to disalign said arrays of orifices with respect to said fittings.

12. A valve for use in an air-to-sea missile delivery system comprising:

a body member having an elongated chamber of open end construction provided with an inlet fitting and an exhaust fitting,

a hollow cylinder of closed end construction housed in said chamber and movable along the longitudinal axis thereof,

5

10

15

20

said cylinder provided with a peripheral array of orifices around the upper and lower portion thereof,

said upper array of orifices aligned with said inlet fitting and said lower array of orifices aligned with said exhaust fitting whereby fluid may flow from said inlet fitting through said upper orifice array into said cylinder and out said lower orifice array into said exhaust fitting,

a reservoir communicating with the upper end of said cylinder,

a pressure actuating shoe housed in said reservoir, said reservoir transmitting a varying downward pressure to said cylinder in response to pressure actuated by said shoe,

a spring actuated plate in contact with the lower end of said cylinder,

said plate transmitting an upward pressure to said cylinder,

whereby in response to an overbearing downward pressure, said cylinder moves along the longitudinal axis of said chamber to disalign said arrays of orifices with respect to said fittings.
